UNITED STATES PATENT OFFICE.

JOHN L. ENNIS, OF READING, PENNSYLVANIA.

SILVER-CLEANER.

1,074,782.

Specification of Letters Patent.

Patented Oct. 7, 1913.

Application filed February 25, 1913. Serial No. 750,472.

To all whom it may concern:

Be it known that I, JOHN L. ENNIS, a citizen of the United States, residing at Reading, in the county of Berks and State 5 of Pennsylvania, have invented certain new and useful Improvements in Silver-Cleaners, of which the following is a specification.

This invention relates to improvements 10 in silver cleansing apparatus and the object in the present instance is to provide a device of the simplest construction, whereby articles of silver, or articles having silver plated surfaces may be thoroughly cleansed.

15 The cleansing is effected through the combined action of an alkaline solution, and the two opposed electrolytically active metals which comprise the device.

The device consists of a flat metal plate 20 having a pair of metal supporting members for the articles to be cleansed, slidably arranged thereon. These metals are such that when they, together with the silver articles to be cleansed, are placed in a suitable receptacle containing an alkaline solution, a galvanic action will be set up which will 25 thoroughly cleanse the surfaces of the silver articles in contact with the sliding members.

The invention is more fully described in 30 the following specification and clearly illustrated in the accompanying drawing, in which I have shown my device in perspective, resting in a suitable receptacle, shown by dotted lines.

35 The numeral 1 designates a flat sheet of metal whose longitudinal edges 2 are bent inwardly toward the upper surface, to form a pair of longitudinal grooves 3. This pan or plate is made of zinc.

40 The numeral 4 designates the sliding members, adapted to support the silver articles to be cleansed. These members 4, of which I have shown two, are preferably made with flat upper surfaces 5 on which

45 the articles to be cleansed are laid, and their ends 6 are bent downwardly and terminate in outwardly projecting lips 7 which fit loosely in, and are adapted to slide in the grooves 3 of the plate 1, and with which

50 they will always be in contact. This sliding action of the supports, which will take

place frequently, due to the loose fit, will insure a clean and positive contact at all times between said members and the plate 1. These members 4 are preferably made 55 of aluminum, but may be made of any other suitable metal which will produce the same result.

The cleansing action is accomplished as follows: The silver articles to be cleansed 60 are placed on the aluminum supporting members 4, and the entire device is placed in any suitable receptacle, as shown by dotted lines 10 in the drawing, into which has been placed a solution of water, common 65 salt and bicarbonate of soda in proportions to make the proper alkaline solution such as is well known and commonly used in connection with devices of this character. The usual galvanic action, set up through 70 the combined action of the zinc plate, the aluminum supporting members and the alkaline solution, will effect the cleansing of the silver articles in contact with the aluminum supports by this well known action, 75 and remove therefrom all surface discolorations and tarnish.

The device is extremely simple and cheap and may be used in any suitable receptacle large enough to receive it together with the 80 solution.

Having thus fully described the invention, I claim:—

1. A device for cleansing silver metal articles comprising a flat sheet of zinc having 85 its longitudinal edges bent up to form a pair of longitudinal grooves, and a plurality of aluminum, metal supporting members formed with lips engaging said grooves, said members being longitudinally slidable 90 in said grooves.

2. In a device of the character described, the combination of a flat plate made of zinc having its longitudinal edges bent to form longitudinal grooves, and a pair of aluminum members formed with lips engaging said grooves and in constant contact with the surface of said plate, said members being longitudinally adjustable in said grooves. 95

3. In a device of the character described, 100 the combination of a receptacle for holding an alkaline solution, a flat sheet of zinc

having its longitudinal edges bent to form a pair of longitudinal grooves, a pair of aluminum supporting members for the articles to be cleansed, said members having their ends bent to form lips, said lips being 5 in slidable engagement with the grooves on the plate and in constant contact with said plate, whereby a galvanic action is set up to

effect a cleansing of the articles in contact with said aluminum supporting members. 10

In testimony whereof I affix my signature in presence of two witnesses.

JOHN L. ENNIS.
